UNITED STATES PATENT OFFICE.

DOUGLAS TURNER, OF ST. LOUIS, MISSOURI, ASSIGNOR TO THE MEASUREGRAPH COMPANY, OF ST. LOUIS, MISSOURI, A CORPORATION OF MISSOURI.

ANTISPINNING DEVICE.

1,336,265.

Specification of Letters Patent.

Patented Apr. 6, 1920.

Application filed April 25, 1919. Serial No. 292,661.

To all whom it may concern:

Be it known that I, DOUGLAS TURNER, a citizen of the United States, residing in the city of St. Louis and State of Missouri, 5 have invented new and useful Improvements in Antispinning Devices, of which the following is a specification.

This invention relates to fabric measuring machines, and has for its object the protection of means for preventing the measuring roll from rotating after the end of the fabric measured has been drawn from between the measuring roll and pressure roll. The machine to which my invention relates 10 is of the type illustrated in various applications of the late Walter E. Hosch, for example, in application Serial No. 17,154, filed March 26, 1915, for cloth measuring and computing machine.

20 In the use of this machine, especially in measuring remnants, the operator frequently draws the fabric through the machine very rapidly with the result that as the fabric passes from between the rollers 25 the measuring roll will be caused to spin, or rotate, to a greater or less extent, thereby causing the dial to indicate a greater length of goods than is actually the case.

To overcome this, the present invention 30 provides a friction member which is adapted to operate immediately upon the passage of the end of the fabric from between the rollers in a manner to substantially lock the rollers against rotation.

35 In the preferred embodiment of the invention, a smooth-surfaced friction disk is mounted co-axially with the measuring roll, but geared to rotate, either in the same or a reverse direction, at a different rate of speed, 40 said friction disk having its smooth surface concentric and substantially flush with the surface of the measuring roll so that the measuring roll and the friction disk will be simultaneously engaged by the pressure 45 roller as soon as the fabric passes from between them, whereby, due to the difference in speed of rotation between the friction disk and the measuring roll, the engagement of the friction disk with the pressure 50 roll will impede the momentum thereof, and the pressure roll will impede the rotation of the measuring roll, with the result that the rotation of the rolls ceases practically simultaneously with the withdrawal 55 of the fabric from between them. The

surface, or periphery, of the friction disk being smooth, offers no appreciable resistance to the passage of the goods between the two rolls, even when the friction disk is geared to rotate in a different direction 60 from the measuring roll. At the same time, the pressure roll being usually of rubber, the engagement between the said roll and the surface of the friction disk will yield the necessary frictional engagement to prevent 65 independent rotation of the disk and pressure roll.

In the accompanying drawings:

Figure 1 is a vertical longitudinal section through the measuring roll on the line 1—1 of Fig. 3;

Fig. 2 is an end view of the measuring and pressure rolls, a portion of the base and chart housing being broken away;

Fig. 3 is a view in rear elevation showing the gearing employed in operating the braking disk; and

Fig. 4 is a plan view of the same gearing.

The numeral 1 indicates the measuring roll which is mounted upon a hollow shaft 80 2 rotating in the bearings 3 mounted in the tubular housing 4, which is attached at its left or rear end to a vertical plate 5 by means of the nut 6. The measuring roll is keyed to its shaft by a spline 7. The 85 shaft of the measuring roll has mounted on its rear end a hub 8 and cam 9, the latter forming a portion of the twelve-yard locking mechanism employed in the machine, but not shown in the present drawings, nor 90 forming a part of this invention. The hub 8 is also used as a mounting for the measuring roll gear 10. Extending through and rotating in the hollow shaft 2 is a spindle 11 which has a bearing also in a sleeve 12 mounted on the bracket 13 at the other end of the measuring roll construction. The spindle 11 has keyed to it, adjacent to the measuring roll 1, a friction disk 14, which is made preferably of a hard and non-resilient substance having the periphery 15 smooth and polished. Motion is transmitted by the measuring roll 1, shaft 2, hub 8 and gear 10 to the spindle 11 and friction disk 14 by means of gears 16 and 17 mounted on 105 a hub 18 and gear 19 rigidly attached to the spindle 11 by means of the bushing 20 and nut 21, so that when the measuring roll is rotated in one direction the friction disk or 110 brake member 14 is rotated at a different

speed either in the same, or a different, direction by means of the gearing described. The gear 22 is an idler gear interposed in the train to reverse the direction of rotation of the friction disk 14. It is evident, however, that the successful operation of this device does not depend on the direction of rotation of the friction disk 14 in reference to that of the measuring roll, but upon the fact that 5 the rotational speed of both members are different. Therefore, the idler gear 22 can be omitted and the direction of rotation of the measuring roll and friction disk will be the same, but their velocities will be different. It is evident, however, that a slightly 10 quicker or greater retarding action will be exerted on the measuring roller when the friction disk is rotated in the reverse direction to that of the measuring roller than 15 when it is rotated in the same direction, although I have not found the difference great enough to be of special moment. I have thought it best to show, however, that such alternative arrangement is within the 20 contemplation of my invention. 25

The operation of the device is as follows: When the fabric is inserted in the machine the pressure roll 23 is in the elevated position shown by the dotted lines in Figs. 1 and 30 2; and when lowered by the starting button, not shown, the fabric is clamped not only between the pressure roll and the measuring roll but between the pressure roll and the polished surface of the friction disk 14 as 35 well. The degree of pressure exerted by the pressure roll is governed by a spring 24 which engages one end of a pivoted arm 25 on the other end of which said pressure roll is rotatably mounted. As the fabric is drawn 40 through the machine, the measuring roll 1 is rotated, and the friction disk 14, although in contact with the under side of the cloth, does not create sufficient friction to retard the movement of the goods, owing to its periphery being smooth and polished. The instant 45 the fabric passes out from between the rolls, the upper roll comes into contact with the friction disk and by virtue of the fact that this pressure roll has a more or less soft 50 surface in comparison with the hard polished surface of the friction disk, the latter will make strong contact with the surface of the pressure roll. On account of the differences in rotational speeds, or directions, or both, 55 of the measuring roll and friction disk, the engagement of the pressure roll with the measuring roll simultaneously with its engagement with the friction disk, will cause the two rolls to be substantially locked 60 against rotation; or, in other words, enough friction will be thrown into the system to greatly reduce the tendency toward spinning and thereby insuring an accurate, or more accurate, reading of the dial than would 65 otherwise be obtained. In fact, even when

the fabric is pulled through the machine at a high rate of speed, the spinning of the rolls is reduced so materially by the friction disk that the resultant effect at the measuring dial is so slight as to be immaterial. In 70 all ordinary use the rolls cease rotating almost instantly with the passing of the goods from between them.

I claim:

1. In a fabric measuring machine, in combination with a measuring roll and a pressure roll adapted to make contact and to be rotated by drawing the fabric to be measured between them, a brake means including a member positioned to be engaged by the pressure roll simultaneously with the engagement of the latter with the measuring roll when the fabric passes from between the rolls. 75

2. In a fabric measuring machine, in combination with a measuring roll and a pressure roll adapted to make contact and to be rotated by drawing the fabric to be measured between them, a brake means including a member having a surface substantially flush with that of the measuring roll and adapted to be engaged by the pressure roll simultaneously with the engagement of the latter with the measuring roll when the fabric passes from between the rolls. 90

3. In a fabric measuring machine, in combination with a measuring roll and a pressure roll adapted to make contact and to be rotated by drawing the fabric to be measured between them, a rotatable brake member, and means whereby said brake member is rotated from the measuring roll at a different rate of speed from that of said measuring roll, said brake member being adapted to be engaged by the pressure roll simultaneously with the engagement of the latter with the measuring roll when the fabric passes from between the rolls. 95 100

4. In a fabric measuring machine, in combination with a measuring roll and a pressure roll adapted to make contact and to be rotated by drawing the fabric to be measured between them, a rotatable brake member, and means whereby said brake member is rotated from said measuring roll 110 at a slower rate of speed than that of said measuring roll, said brake member being adapted to be engaged by the pressure roll simultaneously with the engagement of the latter with the measuring roll when the fabric passes from between the rolls. 115 120

5. In a fabric measuring machine, in combination with a measuring roll and a pressure roll adapted to make contact and to be rotated by drawing the fabric to be measured between them, a rotatable disk mounted coaxially with the measuring roll and of substantially the same diameter and means whereby said disk is rotated from said measuring roll at a different rate of 125 130

speed from that of said measuring roll, said disk being adapted to be engaged by the pressure roll simultaneously with the engagement of the latter with the measuring roll when the fabric passes from between the rolls.

6. In a fabric measuring machine, in combination with a measuring roll and a pressure roll adapted to make contact and to be 10 rotated by drawing the fabric to be measured between them, a rotatable disk mounted coaxially with the measuring roll and of substantially the same diameter and means

whereby said disk is rotated from said measuring roll at a rate of speed different from 15 that of said measuring roll and in a direction opposite to that of the rotation of said measuring roll, said disk being adapted to be engaged by the pressure roll simultaneously with the engagement of the latter with the 20 measuring roll when the fabric passes from between the rolls.

In testimony whereof I have hereunto set my hand.

DOUGLAS TURNER.
